UNITED STATES PATENT OFFICE.

GUSTAV LEIDENROTH, OF KETTWIG-RUHR, GERMANY.

LINE-SPACING MECHANISM FOR TYPEWRITING MACHINES.

Application filed April 15, 1921. Serial No. 461,647.

To all whom it may concern:

Be it known that I, GUSTAV LEIDENROTH, residing at Kettwig-Ruhr, Germany, a citizen of the German Republic, have invented 5 a certain new and useful Improvement in Line-Spacing Mechanism for Typewriting Machines, of which the following is a specification.

The present invention relates to line spacing mechanisms for typewriting machines, in which there is interposed between the paper roller and the line spacing ratchet wheel a clutch which can be thrown out of operation by a member which is independent 10 of the line spacing ratchet wheel, in order to enable the paper roller to be also moved independently of said line spacing ratchet wheel.

The subject matter of this invention is a 20 line spacing mechanism of this kind, in which the member which serves to throw the clutch out of operation is simultaneously able to move the paper roller independently of the line spacing ratchet wheel.

25 The invention will be described with reference to the accompanying drawings which show one embodiment of the subject matter of the invention by way of example and in which—

30 Figure 1 is a central longitudinal section of the mechanism, a portion being broken away, and

Figure 2 is a section on the line 2—2 of Figure 1, seen from the left.

35 The paper roller A is fixed on a hollow shaft C carried in bearings in the frame B of the typewriting machine. Upon the hollow shaft C there is mounted to rotate freely, a line spacing ratchet wheel D which 40 is provided with a milled head d^1 and into the gaps between the teeth of which a locking roller E, mounted on the frame B, is adapted to enter under the action of a spring F. The locking roller allows the 45 ratchet wheel D to rotate in either one direction or the other. The ratchet wheel D is connected to the free end of the hollow shaft C, which is enlarged into a disc c^1 , and by the said hollow shaft C to the paper

50 roller A, by a clamping catch, which can be thrown out of operation. The clamping catch is made double-acting and consists of four balls G and G^1 , each two of the four balls being controlled by a spring H and 55 lying between the cylindrical inner wall d^2 of the ratchet wheel D and an eccentric

face c^2 on the disc c^1 (indicated in Figure 1 by dot and dash lines).

When the parts are in the position shown in the drawing, i. e. the coupling position, 60 the balls G and G^1 are clamped under the action of the springs H between the surfaces c^2 and d^2 , so that they produce a coupling free of play between the ratchet wheel D and the paper roller A (see particularly 65 Figure 2).

In the hollow shaft C there is mounted to rotate loosely a bolt J, provided with a milled head i^1 . Upon the bolt J is rigidly fixed a disc K. In this latter there are 70 provided two recesses h^1 lying opposite each other on one and the same diameter, and embracing, with a certain play, by their lateral boundary faces k^2 , which act as stop faces, screws c^3 fixed in the disc c^1 75 (see Figure 2). The disc K also has four stops k^3 , which project so far into the hollow space between the faces c^2 and d^2 that the balls G and G^1 lie in their path, (see particularly Figure 1).

If the paper roller A is to be moved in dependence on the ratchet wheel D, that is to say, line by line, the milled head d^1 is rotated. In consequence of the coupling produced by the clamping catch c^2 G d^2 between 80 the ratchet wheel D and the paper roller A, this latter follows the rotation of the milled head d^1 and is advanced line by line, the locking roller E dropping back again into a gap between two teeth of the ratchet wheel 90 D after each advance.

If the paper roller A is to be moved independently of the ratchet wheel D, the milled head i^1 is rotated and this according 95 to requirements in one direction or the other. During this rotation, which takes place e. g. in the direction of the arrow α (see Figure 2) the two stops in question, of the four stops k^3 , first come into contact with the two balls G lying in their path 100 and force them out of the locking position. On the further rotation of the milled head i^1 one of the two stop faces k^2 of each recess k^1 comes into contact with the screws c^3 , and the hollow shaft C, and with it the paper 105 roller A takes now part in the rotation of the milled head i^1 while the ratchet wheel D is prevented from rotating by the locking roller E. This rotation is not prevented by the two balls G^1 , which hitherto were still clamped in, as when such rotation takes place the distance apart of the 110

surfaces c^2 and d^2 from each other is increased at the points where the balls G^1 lie. The paper roller A is now rotated until it has advanced as it is desired. When the 5 milled head δ^1 is released the state of the parts shown in the drawing will be automatically restored by the action of the springs H , as will be seen at once without further description.

10 As will result from the above description, only one single member has to be operated for any kind of movement of the paper roller A .

Claims.

15 1. In a line-spacing mechanism for typewriting machines, a platen, a line-spacing ratchet wheel, a clutch mechanism connecting said ratchet wheel to said platen and a hand wheel connected to said clutch for 20 simultaneously disengaging said clutch and rotating said platen independently of said line-spacing ratchet wheel.

25 2. In a line-spacing mechanism for typewriting machines a platen, a line-spacing ratchet wheel, a clutch for connecting said ratchet wheel to said platen and a member operatable independently of said ratchet wheel and engaging said clutch for throwing the same out of operation and for rotating 30 said platen.

35 3. In a line-spacing mechanism the combination with a platen of a line-spacing ratchet wheel, a clutch mechanism associated with said ratchet wheel for connecting said ratchet wheel to said platen, a member secured to said platen and forming an element of said clutch mechanism, tappets carried by said member and means operatable independently of said ratchet wheel for 40 disengaging said clutch and engaging said tappets for rotating said platen.

4. The combination with a platen of a line-spacing mechanism comprising a ratchet wheel, a clutch mechanism associated with said ratchet wheel for operatively connecting the same to said platen, a disk-shaped member secured to said platen and forming an element of said clutch mechanism, tappets carried by said disk-shaped member, and means operatively engaging 45 said clutch for disconnecting the same, said means engaging said tappets for rotating said platen independently of said ratchet wheel and springs for returning said clutch disengaging means to its inoperative position. 50

5. The combination with a platen of a line-spacing mechanism comprising a hollow ratchet wheel, a clutch mechanism for connecting said ratchet wheel to said platen comprising an oval-shaped disk disposed within said ratchet wheel and connected to said platen, tappets carried by said disk, a plurality of clutching balls disposed between the periphery of said disk and the inside face of said ratchet wheel, a second disk-shaped member disposed adjacent said clutch mechanism, said second disk-shaped member being provided with projections adapted to engage said balls and slots for 55 engaging said tappets and means for rotating said second disk whereby said clutching balls will be first moved to an inoperative position and said platen rotated independently of the ratchet wheel by the 60 engagement of said second disk with the tappets carried by said first mentioned disk. 70

The foregoing specification signed at Essen, Germany, this 7th day of March, 1921.

GUSTAV LEIDENROTH.
